SIGNORS OF ONE-THIRD TO LAWRENCE F. MCGRATH, OF PITTSBURGH, PENNSYL-
VANIA.

FLUID PRESSURE DEVICE

Application filed March 18, 1930. Serial No. 436,221.

Our invention relates to fluid pressure devices, and particularly to devices adapted for connection with a source of fluid pressure for indicating when the pressure of such source falls below a predetermined value.

We will describe two forms of fluid pressure devices embodying our invention, and will then point out the novel features thereof in claims.

10 In the accompanying drawings, Fig. 1 is a sectional view, partly diagrammatic, showing one form of fluid pressure device embodying our invention. Figs. 2 and 3 are views showing modified forms of fluid pressure devices
15 also embodying our invention.

Similar reference characters refer to similar parts in each of the several views.

Referring first to Fig. 1, the reference character 1 designates a cylinder upon one end of which is screwed a cap 2. Threaded into the cap 2 is a pipe 3 which communicates with a source of fluid pressure (not shown in the drawings), the condition of which the device embodying our invention is intended to indicate. For example, the pipe 3 may be connected with the main reservoir of the usual and well known air brake system, such as is customarily employed on street railway cars and the like. Into the other end of cylinder 1 is threaded a cylinder head 4, which is provided with openings 5 communicating with the interior of a conical cover 6 attached to the head 4. The cover 6 is open at its upper end, and is provided with a fluid pressure operated signal, here shown as a whistle 7, arranged to be operated by fluid pressure admitted to the cover through the openings 5 in head 4.

40 Reciprocable within the cylinder 1 is a piston 8, which is biased downwardly by suitable means, here shown as a helical spring 9 having one end attached to the piston and the other end attached to the inner surface of the head 4.

45 A pipe 11 is connected at one end with the source of fluid pressure through pipe 3 and terminates at its other end in a port 10 in the wall of cylinder 1. The pipe 11 contains a 50 manually operable valve 12, by means of which the pipe may at times be closed for a

purpose which will be described hereinafter.

The parts are so proportioned that under normal conditions, that is, when the pressure of the source to which pipe 3 is connected is above a predetermined value, the force exerted on the lower side of piston 8 is greater than the force exerted by spring 9 so that the piston occupies the position in which it is illustrated in full lines in the drawings. It will be noted that when the piston occupies this position, it is above the port 10 by means of which pipe 11 is connected with the cylinder, so that the supply of fluid pressure to the cover 6 through openings 5 is interrupted and the whistle 7 is not operated. If, however, the pressure supplied to pipe 3 falls below a predetermined value, the force exerted by spring 9 moves the piston 8 downwardly against the force exerted by fluid pressure on the underside of this piston. This movement of the piston uncovers port 10 and allows fluid pressure to flow through pipe 11 to the upper end of the cylinder 1 above piston 8. The fluid pressure thus supplied to the upper end of the cylinder passes through the openings 5 into the cover 6 and operates the whistle to give a positive indication that the pressure in pipe 3 has fallen below the predetermined value for which the device is intended to operate. Furthermore, the pressure supplied to the upper side of piston 8 through port 10 assists the spring 9 in moving the piston downwardly so that the piston moves smartly to its lower position indicated by broken lines in the drawings. Since the fluid pressure on opposite sides of the piston is now substantially equal, it follows that the piston will remain in its lower position due to the bias of spring 9, and that the whistle 7 will continue to operate, even though the pressure in pipe 3 is again restored above its predetermined value. In order to restore the device to its normal position, the valve 12 may be operated to close pipe 11. If the pressure in pipe 3 is now above the predetermined value, piston 8 will be moved upwardly to its full line position, thereby disconnecting port 10 from the upper end of the cylinder and discontinuing the operation of whistle 7. The valve 12 may now be reopened,

and the device will subsequently operate to indicate a decrease in pressure as described above.

In the modification shown in Fig. 2, the pipe 11 is replaced by a pipe 11^a which connects the port 10 with a port 14 in cylinder 1 at a point below the lowest position of the piston 8. The pipe 11^a may be made integral with the cylinder 1 and contains a restricted orifice 13. With the apparatus constructed as here shown, a decrease in the pressure supplied to pipe 3 below a predetermined value allows the piston 8 to move downwardly in the same manner as described in connection with Fig. 1. When the piston occupies this lower position, however, fluid passing through pipe 11^a operates the whistle 7, but due to the restricted orifice 13, there is a considerable difference in pressure on the two sides of the piston 8. One advantage of this construction is that after the device has been actuated by a decrease in fluid pressure, if the pressure is again restored to a sufficiently high value, the piston 8 will be automatically restored to its upper position, thereby discontinuing the operation of the whistle and restoring the device to its normal condition.

As shown in Fig. 3, the inner wall of the cylinder 1 is provided with a flute or groove 11^b which permits the flow of fluid past the piston 8 when the piston is in its lower position. When the piston is held in its upper position, however, the groove is blanked and no fluid is supplied to the upper end of the cylinder for operating whistle 7. The groove 11^b is preferably proportioned in such manner that the flow of fluid pressure therethrough, while sufficient to operate the whistle 7, allows the piston to be restored automatically to its upper position if the pressure reaches a sufficiently high value. The operation of the modification shown in Fig. 3 is therefore identical with that shown in Fig. 2.

It follows, therefore, that the operation of the devices shown in Figs. 1, 2 and 3 is identical in moving the piston from its normal or its upper position to its lower position, but that in Figs. 2 and 3, the piston will be restored automatically by a sufficient increase of pressure supplied to pipe 3, whereas, in Fig. 1, the valve 12 must be operated to restore the piston.

It should be pointed out that the devices here disclosed may be adjusted to operate at any desired pressure by properly proportioning the various parts. Furthermore, by employing springs 9 of different strengths, the same device may be adjusted to operate at different pressures.

As indicated above, devices embodying our invention are particularly suitable for use in connection with the air brake system of street railway cars. In these systems the pressure available in the main reservoir is

usually indicated by means of the customary gauge, but by the addition of a device embodying our invention, a positive audible indication is given to call the attention of the operator to the condition of the equipment at a critical time, that is, at the instant that the pressure falls below a safe value. 70

While devices embodying our invention are particularly suitable for use in connection with trackway air brake systems, it should be pointed out that they are not limited to such use but are equally applicable wherever it is desired to give a positive indication when the pressure of a source falls below a definite predetermined value. 75

Although we have herein shown and described only two forms of fluid pressure devices embodying our invention, it is understood that various changes and modifications may be made therein within the scope of the appended claims without departing from the spirit and scope of our invention. 80

Having thus described our invention, what we claim is:

1. In combination with a source of fluid pressure, a cylinder containing a piston biased to one position but normally held in another position by pressure from said source, a signal, and a port in the side wall of said cylinder for supplying fluid pressure to said signal if and only if said piston moves away from said other position. 90

2. In combination with a source of fluid pressure, a cylinder containing a piston, means for connecting said source with said cylinder to move said piston to one position, biasing means for moving said piston away from said one position if the pressure of said source falls below a predetermined value, a signal, and a port in the side wall of said cylinder for connecting said signal with said source when said piston is moved away from said one position. 100

3. In combination with a source of fluid pressure, a cylinder having one end connected with said source, a signal connected with the other end of the cylinder, a pipe having one end communicating with said one end of the cylinder and having the other end terminating in a port in the wall of said cylinder, and a piston in said cylinder biased toward said one end of said cylinder and operating to connect said port with one end or the other of said cylinder depending upon the pressure of said source. 110

4. In combination with a source of fluid pressure, a cylinder having one end connected with said source, a signal connected with the other end of the cylinder, a pipe having one end communicating with said one end of the cylinder and having the other end terminating in a port in the wall of said cylinder, and a piston in said cylinder biased toward said one end of said cylinder and operating to connect said port with said other end of 120

the cylinder when the pressure of said source is below a predetermined value but to connect the port with said one end of the cylinder when the pressure is above such predetermined value.

5. In combination with a source of fluid pressure, a cylinder having one end connected with said source, a signal connected with the other end of the cylinder, a pipe having one end communicating with said one end of the cylinder and having the other end terminating in a port in the wall of said cylinder, a piston in said cylinder biased toward said one end of said cylinder and operating to connect said port with one end or the other of said cylinder depending upon the pressure of said source, and a manually operable valve in said pipe.

6. In combination with a source of fluid pressure, a cylinder having one end connected with said source, a signal connected with the other end of the cylinder, a pipe containing a restricted orifice and having one end communicating with said one end of the cylinder and having the other end terminating in a port in the wall of said cylinder, and a piston in said cylinder biased toward said one end of said cylinder but operating to connect said port with said other end of said cylinder only when the pressure of said source falls below a predetermined value.

7. In combination with a source of fluid pressure, a cylinder having one end connected with said source, a signal connected with the other end of the cylinder, a piston biased toward said one end of the cylinder but normally urged to the other end of the cylinder by pressure from said source, said cylinder having a groove which allows the flow of fluid past said piston when the piston is adjacent said one end of the cylinder.

8. In combination with a source of fluid pressure, a cylinder having one end connected with said source, a signal connected with the other end of the cylinder, a piston in said cylinder normally held in one position by fluid pressure in said one end of the cylinder, biasing means constantly urging said piston against the force applied by fluid pressure in such one position to move the piston away from said one position if the pressure of said source falls below a predetermined value, and means operating if said piston moves away from said one position to supply fluid pressure to said other end of the cylinder to operate said signal and to equalize the fluid pressure on opposite sides of said piston.

60 In testimony whereof we affix our signatures.
